UNITED STATES PATENT OFFICE.

JULIUS E. THIELER, OF BROOKLYN, NEW YORK.

ELECTRICAL SWITCH.

Application filed January 19, 1925. Serial No. 3,424.

This invention relates to new and useful improvements in electrical switches and has particular reference to the type of switch shown in my co-pending application Serial 5 #582,734, filed August 18th, 1922, and is adapted for use in connection with indicators and signalling devices as shown therein.

The principal object of the invention resides in the provision of a switch for selectively controlling the operation of a signalling device for displaying indicia and is especially adapted for use upon motor vehicles within reach of the operator of the vehicle.

Another object of the invention is the provision of a switch wherein the switch arm is automatically locked against movement after the same has been manually moved to the selected position thus assuring positive closing of the selected circuit.

With these and other objects in view, the invention resides in certain novel construction and combination and arrangement of parts, the essential features of which are hereinafter fully described, are particularly pointed out in the appended claims, and are illustrated in the accompanying drawing, in which:—

Figure 1 is a top plan view of my improved electrical switch.

Figure 2 is a side elevation of the same.

Figure 3 is a horizontal sectional view on the line 3—3 of Figure 2.

Figure 4 is an enlarged vertical sectional view on the line 4—4 of Figure 1.

The switch 11 includes a pair of circular plates or disks 50 and 51 of insulating material and which are held in spaced relation by posts 52. Contacts 25 are disposed adjacent the periphery on the underside of the plate 51 and interposed between the contacts are depending studs 52' which act as stops for locking the movement of a member 24 when the same is in engagement with the selected contact. Two of the posts 52' serve to limit the movement of the member 24 in either direction. The contact segment 23 is also arranged on the underside of the plate 51 inwardly of the contacts 25 and which terminates radially with the said contacts 25. The control segment 42 is secured to the top face of the plate 50 adjacent the periphery thereof and underlies the contacts 25. The underside of the lower plate 50 is formed with a collar 53 to which is threadedly connected the tube or pipe 54 which supports

the controlling unit and through which the wires from the contacts 25 and contact segments 23 and 42 pass after the wires have been inserted through the opening 53' in the top plate and thence through the eye 54' carried by the lower plate as clearly shown in Figure 4 of the drawing. Wires then pass to the respective parts of the device. The plate 50 further supports a lamp socket 55 for the reception of an electric lamp 56 which is arranged in series with the operating circuit and which serves as a pilot light to indicate to the operator that the signal within the casing is in operation.

The upper face of the plate 51 supports a collar 57 to which is threadedly connected a cylinder 58 closed at its top by a threaded cap 59, and which cap serves as a bearing for one end of a plunger rod 60. The other end of the plunger rod extends below the plate 51 and is bifurcated for pivotal connection as at 51 with the member 24. A spring 62 is interposed between the head of the plunger and the plate 51 and serves to hold the member normally in engagement with the contacts arranged on the underside of the said plate. The inner end of the member 24 carries a wheel 63 for engagement with the underside of the top plate for assisting in the movement of the manual operation of the member to its different radial positions. For bridging the space between the member 24 and the contact segment 23, there is provided a spring finger 64 which disengages the contact member 23 when the member 24 is depressed against the tension of the spring 62 and into contact with the segment 42 when moving the arm to the different radial positions.

The upper plate 51 further supports a contact 65 disposed in the path of movement of the member 24 and the contact 66 arranged in the path of movement of the spring arm 64 and in a radial line with the contact 65 which sets the device in position for actuation of a make and break device (not shown) and with which my suitable switch is adapted for use.

From the foregoing description, it will be seen that in order to move the member 24 in engagement with the respective contacts, it is necessary to depress the same against the tension of the spring 62 and rotate it until the member is moved adjacent the contact desired to be engaged at which time pressure is relieved from the member caus-

ing the spring 62 to positively seat the member in engagement with the contact. Normally, it is impossible to accidentally move the member out of engagement with the desired contact as the studs 52' lock the same against movement and it is necessary to depress the member 24 sufficiently to clear the studs in order to change the position of the member.

10 10 When it is desired that the switch arm be moved to a neutral position, the same may be depressed and released to engage the end of any of the studs which will cause the spring finger to disengage the contact segment 23.

15 What is claimed as new is:—

1. A switch for use in connection with an electrically operated signal comprising a pair of spaced insulated plates, a plurality 20 of radially disposed spaced contacts arranged on the underside of one of said plates, a switch arm, having a wheel thereon at one end for engagement with said last mentioned plate, the other end of said switch 25 arm extending beyond the periphery of said

disks and serving as a manipulating handle, a cylinder mounted upon said plate, a plunger rod operable in said cylinder and extending between said plates and pivoted to said switch arm, and a spring within said cylinder and acting against said plunger to normally hold said switch arm in engagement with said plurality of contacts. 30

2. A switch for use in connection with an electrically operated signal comprising a pair of spaced insulated plates, a plurality of radially disposed spaced contacts arranged on the underside of one of said plates, a switch arm wheel rotatably mounted on one end of said switch arm and movable over the underside of said plate, and means for normally holding said switch arm in engagement within a plurality of contacts, said last means including a spring actuated plunger pivotally connected with said switch 40 arm midway between its ends. 45

In testimony whereof I have affixed my signature.

JULIUS E. THIELER.
